R. PANCOTTI

Des. 96,496

ACCORDION

Filed April 10, 1935

FIG. 1.

FIG. 2.

INVENTOR.
Roberto Pancotti

UNITED STATES PATENT OFFICE

96,496

DESIGN FOR AN ACCORDION

Roberto Pancotti, Brooklyn, N. Y.

Application April 10, 1935, Serial No. 56,288

Term of patent 14 years

To all whom it may concern:

Be it known that I, Roberto Pancotti, a citizen of the United States, residing at No. 1124 Bay Ridge Avenue, Brooklyn, county of Kings, city and State of New York, have invented a new, original, and ornamental Design for Accordions, of which the following is a specification, reference being had to the accompanying drawing, forming part thereof.

I claim:

The ornamental design for an accordion, as shown.

ROBERTO PANCOTTI.
